UNITED STATES PATENT OFFICE.

JOSEPH W. STUBBLEFIELD, OF LOS ANGELES, CALIFORNIA.

FLOOR-SCRAPING MACHINE.

Application filed November 22, 1924. Serial No. 751,845.

This invention relates to wood floor surfacing machines and especially to a power driven means for finishing floors.

It is an object of this invention to provide 5 an improved floor finishing machine which will rapidly and effectively surface a wood floor and give it a smoother surface than has been accomplished by other means heretofore.

10 It is an object to provide a machine operating with a scraping action rather than tearing or grinding of the wood surface. Further it is an object to provide a machine which operates without discoloring or 15 scorching the wood as commonly occurs with various types of surfacers and especially with sanders.

An object is to provide a machine which can be run close up to the wall and thus 20 eliminate the laborious hand work of "pulling the corners" by hand scrapers as is necessary after some forms of machine are run over the floor and which leave large untouched areas at the sides of the flooring 25 near walls to be hand pulled.

It is an object to provide a clean cut surface and a surface which is more nearly level than can be obtained by hand work in far more time of operation.

30 An object is to provide a machine having capacity for instantaneous adjustment, while being propelled across a floor, to regulate the depth of cut.

An object is to provide a combined scraper 35 and suction cleaner with the aim of greatly saving labor and time, and to clean up the chips in front of the cutting means as the machine is advanced.

An object is to provide a machine having 40 a scraping means which acts with a movement of scrapers forwardly in the advancing direction of travel of the machine.

An object is to provide means for running 45 on the smooth finished floor behind the scraping means so as to practically eliminate undulations and vibration of the machine and thereby accomplish a smoothly acting scraping means.

It is an object to provide means for enabling 50 motor propulsion of the machine at will of operator.

An object is to provide a machine of few and substantial parts and of compact organization, and having all parts arranged 55 with the aims of accessibility for inspection, renewal and adjustment.

Other objects and advantages will be made manifest in the following specification of an embodiment of apparatus of the invention, it being understood that modification, variation and adaptation may be resorted to within the spirit of the invention and its scope as here claimed.

Fig. 1 is a left hand, side elevation.

Fig. 2 is a front elevation.

Fig. 3 is a left side view.

Fig. 4 is a vertical section on plane 4, Fig. 3.

Fig. 5 is an end view of the cylinder, broken out.

Fig. 6 is a detail of a helical form of 70 scraping blade and its cylinder, and Fig. 7 is an end view thereof.

Fig. 8 is an end view of a quadruple-edge 75 scraping blade, mounted.

The machine has a suitable frame of top 2 and side walls 3 connected by a dropping flange 4. The rear end of the frame has a 80 caster roller 5, and an upwardly extending push-handle structure including side stiles 6 and a cross bar 7.

On the top 2 is an electric motor M and also a blower B which is connected by belt 8, or other means, to the motor to be driven thereby.

Under the front end of the frame is a cutting or scraping means here shown as including a cylinder 10 having an axle 11 carrying, on one end a sprocket wheel 12 driven by a chain 13 engaging pinion 14 90 on the motor shaft. Various scraping blades may be secured in and along the cylinder 10, which is preferably channelled at 10^a to receive the blades.

I have found, by use, that a blade which 95 has a forwardly hooked corner edge is highly effective. The blade 15 of Fig. 5 has only one hooked, scraping edge 16, while the blade 15 of Fig. 8 has four such effective edges 16 so that the blade can be utilized 100 as a scraper at each of its four longitudinal corners. An effective disposition of such blades in place is at an angle of 60° to a radius cutting the mounted blade. The blade is of an elongated, oblong form in 105 cross-section and perforated to receive screws 18 run into the cylinder 10.

Where necessary, clamp plates 19 may be 110 employed for securing the scraper blades solidly in place.

While the scrapers are shown as straight in Fig. 4, I may employ helical blades 15.

as in Figs. 6 and 7. This form results in a substantially constant acting contact as one scraper follows the other.

A feature of my invention is accessibility.

- 5 To that aim one end of the cylinder has a fixed stop plate 20 and a rotatively shiftable cheek 21 on the other end covering the ends of the cylinder channels. The cheek 21 has a clearance recess 22 which can be registered 70 with the blade ends as the cylinder is rotated slowly, after the cheek has been released by removal of its screws 23.

The scraper means may be removed as a unit by releasing bearing plates 25 secured 15 by screws 26 to the frame walls 3; these being cut away at the front corners. The plates 25 have ball-bearing hubs 27 entering the ends of the cylinder 10 for compactness.

Each plate is apertured at 28 to provide 20 for access to the ends of the scraper blades, as for the insertion of a cold chisel, Fig. 4 to drive out a scraper blade after its screws 18 have been withdrawn, and the cheek freed to turn.

25 The cylinder is so driven as to sweep the blades 10 forwardly and up, as indicated, in direction of advance of the machine. This shears off the floor surface in a quick, clean and smooth manner without generating heat 30 enough to discolor the wood. This is an important advantage of the present machine.

The lifted cuttings are gathered by a suction mouth-piece 30 disposed just in front of and along the cylinder and clear of the 35 sweep of the blades. From the mouth-piece a conduit 31 leads to the blower and from this to an air-pervious bag R receiving the cuttings and dust.

I provide for instantaneous adjustment of 40 depth of cut. For this result a roller 33 is positioned in front of the suction mouth 30 and has bearing in end slides 34 shiftable in guides 35 on the side plates 25. The upper ends of the slides engage cams 36 having 45 gears 37 engaging worms 38 on a rock-shaft 39. This rock-shaft extends across the top 2 and has a lever arm 40 from which a link 41 extends up and connects to a hand-lever 42 pivoted on a handle stile 6. A rack and 50 ratchet 43, near the bar 7, enables quick and lockable adjustment of the roller 33 by means of the cams and worms.

The machine may be propelled by hand or 55 motor power. In the latter case the motor shaft has a worm 45 engaging a gear 46 on an upright shaft 47 having a bearing 48 to swing on the motor hub. The lower end of shaft 47 is in a bearing 49 slotted on an arc so that it can swing about the motor hub 60 and be set by screws 50. The shaft has a worm 51 to engage a gear 52 on a shaft 53 carrying a roller 54 having vertically adjustable end bearings 55.

65 By my present machine I have accomplished one very important object, and that

is,—completely finishing the surfacing by and in one operation of the machine thus eliminating the several, various steps ordinarily required by other types of machine commonly used.

70 By actual experience with operation of the present invention, I have demonstrated that efficient and rapid results are obtained by employing blades which have "hooked" edges of different sizes; the smaller hooks 75 producing fine cuts and a clean smooth surface for finish work, while coarser hooks are effective for rougher surfacing. Also the differently hooked scrapers are variously adaptable for use on the several kinds of 80 wood, according to hardness.

It is understood that the present machine has many other uses than that of floor surfacing only, here mentioned.

85 As the machine is advanced the surface of the floor is scraped off smooth behind roller 33 and the machine is steadied by a transverse roller 58 which bears on the finished floor from which all "top wood" has been taken off by the scrapers.

90 A clutch 59 controls driving gears 51—52 for advancing the machine at will by power of the motor.

95 What is claimed is:

1. A floor scraping machine having, in combination, a frame provided with detachable side bearing plates at the front end and which have apertures, and a cylinder mounted between the plates and having longitudinal blades which are removable endwise 100 through the said plates without necessitating removal of the plates.

105 2. A floor scraping machine having, in combination, a rotative scraping means, rolling supports, a front adjusting roller, bearing slides for the roller, a handle bar, and means for adjusting the slides and including a hand-lever adjacent to the handle bar, a cam device for each slide, and connecting mechanism between said cams and the hand lever for shifting the slides.

110 3. A floor scraping machine having, in combination, a frame provided with detachable side bearing plates having apertures, and a cylinder mounted between the plates and having longitudinal scraping blades removable endwise through the plates, and turnable, cheek plates on the ends of the cylinder, each having a recess registerable with the ends of the blades for the insertion 115 and removal thereof.

120 4. In a floor scraping machine, a rotative carrier provided with longitudinal recesses tangential to the axis of the carrier, and an elongated bit in each recess, each bit having a pair of outwardly curled scraping corners along each longitudinal edge, said recess being laterally widened at its bottom to clear the out curled corners of the inserted bit, and means for clamping the bits along the 125 130

carrier; said bits being reversible end for end and side for side in the recesses.

5. A floor scraping machine having, in combination, a rotative cutting means including effective transverse scraping blades, a steadyng roller disposed at the rear of said means and running on the floor finished by said means, and rolling means including a roller extending across in front of the 10 cutting means and having concurrently adjustable slides for regulating the depth of cut, said slides being combined with means whereby they are instantly and uniformly adjusted.

15. 6. A floor scraping machine having, in combination, a rotative cutting means having transverse scrapers, a steadyng roller close to the rear of said means and travelling on the finished surface, and an unyielding 20 adjustable roller in front of the cutting means to regulate the depth of cut and having operatively connected, adjusting slides, said slides being combined with means whereby they are instantly and uniformly 25 adjusted.

7. A floor scraping machine having, in combination, a rotative scraping means, a steadyng roller close to the rear of the

scraping means and running on the finished surface, an adjustable rolling means in front 30 of the scraping means, and manually operable means including connected, sliding bearings to instantly adjust the rolling means, said slides being combined with means whereby they are instantly and uniformly 35 adjusted.

8. A floor scraping machine having, in combination, a frame, a motor thereon, rolling means supporting the frame, handle means for manual propulsion of the machine, 40 a motor-driven, scraper-bladed cylinder, an adjustable traction roller for motor propulsion of the machine, traction roller driving gearing including a swinging shaft geared to the motor shaft and an adjustable gear bearing for the swinging shaft; whereby to disconnect driving gears when the roller is retracted to non-driving position.

9. A floor scraping machine having, in combination, scraping means, rolling supports behind the same, a front roller, a hand-lever, bearing slides for the roller, cams engaging the slides, a rock-shaft geared to the cams, and an operating connection between the rock-shaft and the hand-lever.

J. W. STUBBLEFIELD.
